LITTER PAN FOR CATS

Robert W. Brickel, 483 Sharon Drive,
Rochester, N.Y. 14626

Filed Apr. 6, 1972, Ser. No. 241,865

Term of patent 14 years

Int. Cl. D30—99

U.S. Cl. D30—99

FIG. 1

FIG. 2

FIG. 3

FIG. 4

FIG. 5

FIG. 6

FIG. 1 is a top plan view of a litter pan for cats embodying my new design;

FIG. 2 is a front end elevational view thereof;

FIG. 3 is a rear end elevational view thereof;

FIG. 4 is a side elevational view thereof;

FIG. 5 is a bottom plan view thereof; and

FIG. 6 is a sectional view taken along the line 6—6 in FIG. 4 looking in the direction of the arrows.

I claim:

The ornamental design for a litter pan for cats, substantially as shown.
